US00D356964S

United States Patent [19]

Turo et al.

[11] **Patent Number:** Des. 356,964[45] **Date of Patent:** ** Apr. 4, 1995

[54] **HOUSING FOR HOLDING AND
DISPENSING ELECTRONIC
THERMOMETERS**

[75] Inventors: **Steven J. Turo**, Sandy Creek;
Frederick C. Deno, Brownville, both
of N.Y.

[73] Assignee: **Sherwood Medical Company**, St.
Louis, Mo.

[**] Term: **14 Years**

[21] Appl. No.: **13,239**

[22] Filed: **Sep. 21, 1993**

[52] U.S. Cl. **D10/60; D10/57**

[58] **Field of Search** D10/57, 60; 206/306,
206/443, 526; 374/158, 183, 208, 209

[57] **CLAIM**

The ornamental design for a housing for holding and dispensing electronic thermometers, as shown and described.

DESCRIPTION

FIG. 1 is a perspective view of a housing for holding and dispensing electronic thermometers showing our new design;

FIG. 2 is a top plan view thereof;

FIG. 3 is a rear view thereof;

FIG. 4 is a bottom plan thereof;

FIG. 5 is a left side view thereof, the right side view being identical; and,

FIG. 6 is a front view thereof.

FIG. 1

FIG. 2

FIG. 3

FIG. 4

FIG. 5

FIG. 6
